(57) **CLAIM**

The ornamental design for a fluid bed machine with storage cabinet, as shown and described.

DESCRIPTION

FIG. 1 is a perspective view of the fluid bed machine with a storage cabinet according to the present invention.

FIG. 2 is a front elevation view of the machine.

FIG. 3 is a left side elevation view of the machine.

FIG. 4 is a right side elevation view of the machine; and,
FIG. 5 is a top plan view of the machine.

Applicant makes no claim to the bottom view of the machine or to the structure shown in broken lines in the drawings.
